UNITED STATES PATENT OFFICE

115,150

DESIGN FOR AN INSECT TRAP

Darwin S. Karr, Los Angeles, Calif.

Application March 29, 1939, Serial No. 83,908

Term of patent 14 years

To all whom it may concern:

Be it known that I, Darwin S. Karr, a citizen of United States, residing at Los Angeles, county of Los Angeles, and State of California, have invented a new, original, and ornamental Design for an Insect Trap, of which the following is a specification, reference being had to the accompanying drawing, forming a part thereof, wherein:

Figure 1 is a perspective view of an insect trap showing the new design.

Figure 2 is a view in elevation looking at the rear end of the trap.

I claim:

The ornamental design for an insect trap, as shown.

DARWIN S. KARR.
